UNITED STATES PATENT OFFICE

155,036

DESIGN FOR A CHILD'S SHIRT

Joseph A. Rielly, New York, N. Y., assignor to Rielly Company, Inc., New York N. Y. a corporation of New York

Application August 3, 1948, Serial No. 147,911

Term of patent 14 years

(Cl. D3—4)

To all whom it may concern:

Be it known that I, Joseph A. Rielly, a citizen of the United States and a resident of the city of New York (Borough of Queens), in the county of Queens and State of New York, have invented a new, original, and ornamental Design for a Child's Shirt, of which the following is a specification, reference being had to the accompanying drawing, forming part thereof, in which the back of the article is conventionally plain and the single figure is a front elevation of a child's shirt showing my new design.

I claim:

The ornamental design for a child's shirt, as shown and described.

JOSEPH A. RIELLY.
